Company, Ypsilanti, Mich., a corporation of
Michigan

Application August 3, 1942, Serial No. 453,404

5 Claims. (Cl. 126—44)

This invention relates generally to cook stoves having fluid type burners and refers more particularly to an improved oven heating arrangement for such stoves.

It has been the usual practice in the manufacture of electric and gas burning cook stoves equipped with ovens to regulate the oven temperatures by a thermostat installed in a manner to vary the supply of the particular heat producing energy in response to temperature variations in the oven. The use of thermal controlled means to regulate the operation of the heating elements in an electrically heated oven and to regulate the flow of fluid in gas heated ovens has been found to be satisfactory for securing a wide range of different temperatures in the oven and for maintaining the temperature of the oven reasonably uniform at any one of the preselected temperatures in the range. This more or less satisfactory operation is perhaps due to the fact that the heat producing energy in both the above instances responds practically instantaneous to operation of the thermostat.

However, the principle of oven control briefly outlined above has proved very unsatisfactory when applied to liquid burning stoves of the type having a wick located in a channel supplied with the liquid fuel from a suitable source by the action of gravity. In applying the thermostat control principle to a liquid burning stove of the above type, the thermostat is employed to regulate the supply of liquid to the wick channel. The arrangement is such that if the temperature in the oven exceeds the preselected temperature, the thermostat closes a valve which shuts off further flow of fluid from the source to the wick channel. However, the burner flame is not immediately reduced because of the fluid contained in the channel and the temperature in the oven continues to rise until sufficient fuel is burned to substantially lower the flame. The flame is eventually lowered below the amount required to maintain the preselected oven temperature before the valve is again opened and the temperature in the oven may fall substantially below the preselected temperature before sufficient fluid is supplied to the channel to raise the flame the required amount. Thus, it will be seen that the temperature in the oven will fluctuate over a relatively wide range and that it is practically impossible to maintain a uniform preselected temperature in the oven.

Moreover, in attempting to thermostatically control ovens heated by liquid burners of the character set forth, difficulty has been encountered in maintaining temperatures in the lower

regions of the adjustable range without completely extinguishing one or more of the burners. Extinguishing one or more of the burners is, of course, objectionable especially in cases where it is desired to subsequently raise the oven temperature because it entails again igniting the burner.

10 The present invention contemplates overcoming all of the above objections by providing a liquid burner oven construction with means which not only renders it possible to secure and to more uniformly maintain any one of a number of preselected temperatures in the oven but, in addition, enables obtaining a sufficiently low temperature in the oven for all practical purposes without extinguishing any one of the burners.

15 In accordance with this invention, the oven temperature is controlled without the use of thermostats or equivalent thermal responsive means by merely relatively vertically adjusting the reservoir or source of supply and the burners to vary the elevation of the burner channels with respect to the level of the fluid in the reservoir. As a result, the quantity of fluid in the burner channels is increased or decreased depending upon the direction of relative adjustment and the flame of the burners is substantially instantaneously correspondingly effected.

20 30 Another object of this invention is to support the burners at different elevations so that at least one of the burners burns at a greater intensity than the other. This arrangement is largely responsible for the ability of burners to provide and maintain a uniformly low temperature in the oven.

25 35 Still another object of this invention is to provide a control supported for manipulation at a convenient point remote from the burners and operatively connected to the burners for raising and lowering the same relative to the reservoir throughout predetermined increments of travel which correspond to different temperatures in the oven.

40 45 A further object of this invention is to provide means for directing the heat generated by the burners in the oven so that the heat is uniformly distributed even though one burner is burning at a different intensity than the other.

50 55 The foregoing, as well as other objects, will be made more apparent as this description proceeds, especially when considered in connection with the accompanying drawings, wherein:

Figure 1 is a front elevational view of a stove constructed in accordance with this invention;

Figure 2 is a side elevational view of the stove

shown in Figure 1 with certain parts broken away for the sake of clearness;

Figure 3 is an enlarged front elevational view of the burners and support therefor;

Figure 4 is a sectional view taken on the line 4—4 of Figure 3;

Figure 5 is a sectional view taken on the line 5 5—5 of Figure 3;

Figure 6 is a rear elevational view of a part of the control operating mechanism;

Figure 7 is a side elevational view of the construction shown in Figure 6; and

Figure 8 is a plane view of a part of the plumbing employed.

In Figures 1 and 2 of the drawings it will be 15 noted that the reference character 18 designates a cook stove having the usual base section 11 and having an oven 12 supported above the base 11 in vertical spaced relation thereto by means of a suitable frame structure 13. The space between the top of the base 11 and the bottom of the oven 12 forms a compartment 14 of sufficient dimension to receive the burner assembly 15 for the oven. Both the oven and the compartment 14 are adapted to be closed by the usual doors 16 and 17, respectively. The doors are suitably hingedly supported at their bottom edges in a manner to enable the same to be readily opened when it is desired to gain access to the interior of the oven 12 and burner compartment 14. The burner assembly 15 is shown in Figures 1 to 4, inclusive, as comprising a support 19 and a plurality of burners 20 fixed on the support 19. In the present instance, two burners are shown and these burners are of the wick oil burning type. Although any one of a number of accepted designs of wick type oil burners may be used, nevertheless, the one shown in the several figures of the drawings is preferred. In general, each burner 20 comprises an annular fuel retaining channel 21 and a burner drum 22 suitably supported at its lower end on the upper end of the channel. The upper end of each annular channel 21 is closed by a flame spreader 23 in the form of a disc having the periphery seated on the upper edge of the inner flange of the channel and having the central portion dished in an upward direction to provide an annular inwardly tapering wall 24. The wall 24 is apertured in the manner indicated in the drawings to enable air to pass laterally outwardly across the upper end of the channel.

Upon reference to Figure 3 it will be noted that a rod 25 extends upwardly through the support 19 in concentric relation to the channel 21 and projects through the top wall of the flame spreader. The rod is secured to the support 19 and the upper end thereof is threaded to receive a clamping nut 26 which serves to secure the flame spreader 23 and the annular channel 21 on the support 19.

An annular wick 27 is supported in each of the channels 21 and the upper end of the wick extends a limited distance beyond the corresponding end of the channel. As shown particularly in Figure 5 of the drawings, each wick 27 is provided with a pilot in the form of a relatively small section 28 of the wick material which is stapled or otherwise fixedly secured to the outer surface of the wick and extends downwardly below the base of the channel 21 into the fuel supply conduit 29.

The fuel supply conduits 29 of the two burners are connected together by means of a T-shaped coupling 30 which is connected to a reservoir 31

5 by means of an intake conduit 32. The reservoir 31 is shown in Figure 1 as supported in a compartment 33 located adjacent the compartment 14 and adapted to be closed by a suitable door 17. The reservoir is adapted to contain a supply of fuel to the level indicated by the dot and dash line 35 and is supported on the dividing wall between the two compartments 14 and 33 at such an elevation with respect to the burner channels 21 that fuel flows by the action of gravity into the channels 21.

With the construction described above it will be noted that the intensity of the flame of each burner may be varied by altering the elevation of the burners with respect to the level 35 of the fuel in the reservoir 31. In order to accomplish this result, the support 19 for both burners is vertically adjustable in the compartment 14 relative to the reservoir 31 in the compartment 33. In detail, the support 19 is slidably mounted on a pair of sheet metal plates 36 having the lower ends rigidly secured to the base 11 at points spaced from each other in the direction of length of the support 19 and having laterally outwardly projecting vertically spaced ears 37 apertured for slidably receiving the rods 25. The inner surfaces of the plates 36 respectively slidably engage the base portions of a pair of inwardly opening channel shaped brackets 38 having the upper flanges 39 secured to the support 19.

The brackets 38 are respectively supported on the plates 36 through the medium of a pair of cams 40 secured to a rock shaft 41. The opposite ends of the rock shaft 41 project through suitable openings in the brackets 38 and are respectively rotatably mounted on the plates 36. The spacing of the cams 40 on the rock shaft 41 is such that these cams respectively occupy positions in the channels of the brackets 38 and contact with suitable angle brackets 42 to support the member 19 with the burners 20 thereon. As shown particularly in Figure 3, the angle brackets 42 are respectively secured to the base portions of the channels 38 and cooperate with the lower flanges 43 on the channels 38 to respectively engage diametrically opposite sides of the two cams 40.

It follows from the above that rocking movement of the shaft 41 in opposite directions raises and lowers the burner support 19 to vary the elevation of the burner channels 21 relative to the level 35 of the fuel in the reservoir 31. In other words, rocking of the shaft 41 controls the quantity of fuel in the channels 21 of the burners and, therefore, correspondingly controls the intensity of the flame generated by each burner.

In the present instance, the shaft 41 is rocked by a rotatable control element 44 mounted on the stove for convenient manipulation by the operator. As shown in Figures 1 and 2, the control element is rotatably supported on the apron 45 which extends above the top of the oven at the back of the stove. The control element 44 comprises a knob 45' secured to a suitable rock shaft 46 and having a pointer 47 adapted to move along a scale 48 which is graduated in different degrees of oven temperature. The rock shaft 46 is supported in a bracket 49 which, in turn, is welded or otherwise fixedly secured to the apron 45 and is provided with a vertical guide 50 for slidably receiving a rack 51. The teeth on the rack mesh with a pinion 52 which is secured to the rock shaft 46 and is operated by the latter to reciprocate the rack 51.

The lower end of the rack 51 is secured to the upper end of the rod 52 by means of an adjustable connection 53 and the lower end of the rod 52 is connected to one end of a bell crank lever 54. The lever 54 is pivotally supported intermediate its ends on a bracket 55 which is fixedly secured to the base 11 of the stove within the compartment 14. The free end of the bell crank lever is pivotally connected to one end of a link 56 having the opposite end pivotally connected to the lower end of an arm 57 having the upper end fixed to the rock shaft 41 intermediate the ends of the latter.

The above arrangement is such that rotation of the control 45' in a clockwise direction to increase the oven temperature lowers the rack 51 and rotates the cams 40 in a direction to lower the burners 20 with respect to the level 35 of the fuel in the reservoir 31. On the other hand, rotation of the control 45' in a counterclockwise direction to decrease the oven temperature raises the rack 51 and rotates the cams 40 in the opposite direction to raise the burners 20 with reference to the level 35 of the fuel in the reservoir 31.

It follows from the above that the angular locations of the complementary cams 40 with respect to the burner support 19 must be predetermined in relation to the control 45' to support the burners at the elevations required to heat the oven to the temperature indicated by the dial indicator 47 on the control 45'. The proper relationship between the complementary cams 40 and the control 45' is obtained by adjusting the connection 53 between the rack 51 and the rod 52. It will also be noted that the control 45' is yieldably held in any one of its various adjusted positions by means of a spring detent 58. The spring detent 58 is in the form of a flat spring having one end rigidly secured to the bracket 49 and having the opposite end fashioned to successively engage in the notches 59 formed in one edge of the rack 51. Each notch 59 in the rack 51 corresponds to one setting of the control 45' so that these notches cooperate with the detent 58 to hold the parts in any one of the preselected settings. Attention is also called at this time to the fact that an additional notch 60 is formed in the rack 51 adjacent the lower end of the latter. This notch corresponds to the "off" position noted on the indicating dial and cooperates with the detent to hold the parts in a position wherein the burner channels 21 are supported above the fuel level 35.

Raising and lowering of the burners 20 is permitted without interfering with the supply of fuel to the burners by forming the intake conduit 32 of a plurality of sections and by connecting the sections with swivels joints. Upon reference to Figure 8 it will be noted that the intake conduit is formed of three section 60', 61 and 62. The section 60' is connected directly to the reservoir 31 adjacent the bottom of the latter by means of a nipple 63 and is connected to the section 61 by means of a swivel joint 64. The arrangement is such as to permit the sections 61 and 62 of the intake conduit 32 to swing upwardly and downwardly relative to the section 60' or relative to the reservoir 31. The section 62 is connected to the free end of the section 61 by means of a swivel coupling 65 and is bent at right angles adjacent the free end for connection with the T-shaped coupling 30. As a result, the burners 20 and associated supply conduits 29 are permitted to move upwardly and downwardly relative to the reservoir 31 without interfering with the flow of fuel from the

reservoir to the burners and without incorporating flexible conduits.

It has been stated above that difficulty has been encountered with burners of the type shown herein in maintaining oven temperatures in the lower portion of the range without completely extinguishing one of the burners. In accordance with the present invention, the above objection is overcome by supporting one burner at a lower elevation than the other and for this purpose the support 19 is recessed as at 66. This recess enables supporting the right hand burner (as viewed in Figures 1 and 3) below the left hand burner. This arrangement is such that when it is desired to operate the oven at the minimum or at relative low temperatures, the support 19 is raised to a point where the channel of the left hand burner assumes a position above the level of the fuel in the reservoir 31. When this condition exists, only the pilot portion of the left hand burner is burning and the intensity of the flame generated by the right hand burner is substantially reduced. As a result, the oven may be maintained at relatively low temperatures without the necessity of extinguishing one of the burners.

Upon reference to Figure 2 it will be noted that the bottom wall 67 of the oven is formed with a slot 68 directly above the burner drums 22 to enable the heat generated by the burners to enter the oven. The heat passing upwardly through the slot 68 is distributed in the oven by a baffle plate 69 having the opposite ends suitably secured to the side walls of the oven and having a depending longitudinally extending substantially V-shaped projection 70 located in the path of the heat passing through the slot 68. The projection 70 is inclined with respect to a horizontal plane and is located above the burners with the lower end positioned above the lowermost burner and with the upper end positioned above the other burner. Also the rear wall 70 of the V-shaped projection is inclined to a lesser degree than the front wall so that a substantial amount of heat is directed toward the rear of the oven. This construction insures uniform distribution of the heat throughout the oven and contributes materially to obtaining highly efficient oven operation.

Operation

When the control 45' is in a position wherein the point 47 registers with the "off" position on the indicator dial 48, the burners 20 are elevated to a position wherein the lower ends of the pilot wick sections 29 are above the fuel level 35. In other words, both burners are extinguished and must be lowered before they can be ignited.

Assuming that the parts are in the above position and that it is desired to heat the oven 12 to a temperature of approximately 400° F., the operator merely turns the control 45' in a clockwise direction to register the indicator 47 with the graduation on the dial 48 corresponding to the desired 400° temperature. When the control 45' is rotated in a clockwise direction, both the burners 22 are lowered through the mechanism previously described connecting the control to the cam rock shaft 41. As stated above, the support 19 for both burners rests directly on the complementary cam 40 so that as the high points of the latter are lowered the burner support is correspondingly lowered.

When the burners are in the above position,

the base portions of the channels 21 of both burners assume positions below the level 35 of the fuel in the reservoir 31. As a result, fuel is permitted to flow by gravity into the channels and more fuel is, of course, supplied to the right hand burner due to its lower elevation. The two burners are then ignited and the combined heat produced by the two burners will eventually raise the oven temperature to 400° which corresponds to the preselected setting. In other words, the relation between the control 45' and the complementary cams 40 is such as to insure locating the burners in such relation to the oil level 35 that the combined intensity of the two burners is sufficient to heat the oven to the 400° setting. Thus, the temperature of the oven is controlled by adjusting the elevation of the two burners with respect to the fuel level in the reservoir 31 and this arrangement is not only more accurate because of the characteristics of the fuel employed but is also simpler and less expensive to produce.

What we claim as our invention is:

1. A stove comprising a plurality of fluid burners, a fluid reservoir communicating with said burners and supported at such an elevation with respect to the burners that fluid flows by gravity to the burners, means for supporting said burners in fixed relation to each other at different elevations with respect to each other, and means for relatively vertically adjusting the reservoir and burners to vary the elevation of the level of the fluid in the reservoir with respect to the elevations of said burners.

2. A stove comprising a plurality of burners each having a channel for receiving the fluid, a reservoir communicating with the channels of the burners and supported at such an elevation with respect to the channels that fluid flows by gravity to said channels, a vertically adjustable member for supporting the burners in fixed relation to each other at different elevations with respect to each other, rotatable cam means supporting said member, and means accessible from a point remote from the burners for rotating the cam means

45 in opposite directions throughout predetermined increments of travel which correspond to pre-selected temperatures.

3. A stove having an oven provided with an opening in the bottom wall and having a plurality of fluid burners located below the oven in registration with the opening, a fluid reservoir communicating with the burners and supported at such an elevation with respect to the burners that fluid flows by gravity into the burners, means for supporting the burners in fixed relation to each other at different elevations with respect to each other and means for uniformly distributing the heat supplied by the burners throughout the oven.

10 4. A stove having an oven provided with an opening in the bottom wall and having a plurality of fluid burners located below the oven in registration with the opening, a fluid reservoir communicating with the burners and supported at such an elevation with respect to the burners that fluid flows by gravity into the burners, means for supporting the burners in fixed relation to each other at different elevations with respect to each other and baffle means located in the oven above the opening for directing the greater heat supplied by the lowermost burner laterally toward the portion of the oven served by the other burner.

15 5. A stove comprising a plurality of burners each having a channel communicating with a depending supply conduit, an annular wick located in each channel and having a pilot extension projecting downwardly into the adjacent supply conduit, a fluid reservoir communicating 20 with the supply conduits and supported at such an elevation with respect to the channels that fluid flows by gravity into the channels, means for supporting the burners in fixed relation at different elevations with respect to each other 25 and means for vertically adjusting the burner supporting means relative to the level of fluid in the reservoir to vary the quantity of fluid in said channels from zero to a predetermined maximum.

CARROLL M. BREED.
HERMAN KIRCHHOFER.
